RELEASABLY INTERLOCKED GRINDING MECHANISM

Nathan Obedin, Brooklyn, N. Y.

Application October 30, 1944, Serial No. 561,108

2 Claims. (Cl. 51—248)

This invention relates to improvements in portable cloth cutting machines of the kind that are adapted to be moved about by hand on a cloth-cutting table, the cutting machine having a disk-shaped motor driven rotary cutter.

An object of this invention is to provide an improved grinding device which is pivotally mounted on the motor and having two rotatably supported grinding wheels straddling the cutter and adapted to be jointly swung into contact with the cutter for grinding and sharpening the cutter during its rotation by the motor.

Another object of this invention is to provide cup-shaped retainers for rotatably supporting the grinding wheels by interlocking engagement and without cementing the grinding wheels in the retainers.

Another object of this invention is to provide means for detachably securing each of the grinding wheels for rotation on an axle, the said means comprising a cup-shaped retainer rotatably mounted on an axle, the retainer having apertures positioned on diametrically opposite sides and to provide keyways in the grinding wheel, and a clamping disk having a central aperture and pins on diametrically opposite sides of the aperture, the pins passing through the keyways and through the apertures in the retainer and serving to transmit torque on the grinding wheel to the retainer.

Another object of this invention is to provide an annular leaf spring having corrugations therein and adapted to be secured intermediate a clamping disk and a grinding wheel in a retainer to absorb shock imparted to the grinding wheel.

With the above and other objects in view, the invention will be hereinafter more particularly described, and the combination and arrangement of parts will be shown in the accompanying drawing and pointed out in the claims which form part of this specification.

Reference will now be had to the drawing, wherein like numerals of reference designate corresponding parts throughout the several views, in which:

Figure 1 is a perspective view of a cloth-cutting machine having a disk-shaped motor driven rotary cutter and provided with an improved duplex grinding mechanism embodying the invention.

Figure 2 is a central cross-sectional view of the duplex grinding mechanism, showing releasably mounted grinding wheels.

Figure 3 is a plan view of a grinding wheel retainer.

Figure 4 is a plan view of a releasable grinding wheel.

Figure 5 is a plan view of a pin-carrying disk for a grinding wheel.

Figure 6 is a plan view of an annular spring having corrugations therein.

Figure 7 is a central cross-sectional view of a modified grinding wheel mounting, showing the annular spring inserted between the grinding wheel and the wheel retainer.

A common means utilized for fixing a grinding wheel to a wheel retainer is to cement the wheel to the retainer. When it is desired to remove a used grinding wheel and to replace it with a new wheel it is necessary to heat the wheel retainer and the worn grinding wheel to soften the cement. This proceeding is obnoxious due to the odor generated by the heat and there are complaints by the people in the cutting room.

In the disclosure herewith there is formed a mechanical interlock for the grinding wheel with the wheel retainer. The mechanical interlocking of the grinding wheel with the wheel retainer does away with the heating operation and the resultant obnoxious smell created thereby.

In the illustrated embodiment of the invention, the numeral 10 indicates a portable cloth-cutting machine having a disk-shaped cutter 11 driven by an electric motor 12 and movable on cutting tables on a base 13 integral with the motor, as is well known in the art.

For the purpose of grinding and sharpening the disk-shaped cutter 11 during its rotation, there is provided a grinding attachment 15, comprising a housing 16 having a pivot-pin 17 passing therethrough. The pin 17 is received in an arm 18 fixed to the motor housing.

The grinding attachment 15 has two grinding wheels 19, which are spaced apart from each other. The wheels 19 are housed in cup-shaped wheel retainers 20. Each retainer has an integral spindle 21 designed for rotation in a bearing member 22. The attachment 15 is thus pivotally mounted and may be swung down to bring the grinding wheels 19 into grinding engagement with the cutter 11.

The bearing members 22 have threads 23 on their outer surfaces which engage threads in arms 24 integral with the housing 16. Screws 25 threaded in the spindles 21 hold the retainers 20 in rotatable relation in the bearing members 22. The bearing members 22 may be adjustably rotated to bring the grinding wheels 19 to or away from the cutter 11.

The mechanism disclosed herewith for releas-

ably securing each grinding wheel 19 to a wheel retainer 20 consists in part in forming keyways 26 extending through the flange 27 of the grinding wheel 19. I employ a centrally apertured disk 28 having a plurality of pins 29 integral with the disk and positioned diametrically thereof. A central aperture 30 in the disk 28 is preferably countersunk to receive the head of a flat head screw 31.

I also provide apertures 32 positioned diametrically of the wheel retainer 20. The apertures 32 are in alinement with the keyways 26 in the grinding wheel 19 and with the pins 29 in the disk 28. In practice, the spindle 21 has an enlarged head 33 by means of which the spindle is suitably fixed to the wheel retainer 20.

In operation, a grinding wheel 19 is placed in a wheel retainer 20 with the keyways 26 and the apertures 32 in alinement. The disk 28 is then mounted inside a hollow portion 34 of the grinding wheel 19, with the pins 29 passing through the keyways 26 and through the apertures 32. The screw 31 is then threaded into a tapped hole in the head 33 and tightened to bring the grinding wheel 19 into engagement with the inner surface of the wheel retainer 20.

Grinding mechanism of the character here described is subject to shocks and a degree of vibration. To readily cushion and absorb these shocks and vibrations I provide an annular resilient spring 36 having a corrugated or undulated surface. The spring 36 is placed between the cup-shaped retaining member 20 and the grinding wheel 19.

The spring 36 serves to press the grinding wheel 19 into frictional engagement with the wheel retainer 20.

The spring 36 may be made of flat thin spring-steel and have a series of lateral undulations or waves 37 pressed therein. The undulations make the annular surface resilient so that it tends to rebound.

The resilient spring 36 permits the clamping disk 28 to be tightened only enough to hold the grinding wheel 19 firmly, thus avoiding unnecessary strain. The resilient spring 36 distributes the pressure evenly when the disk 28 is tightened against the grinding wheel and the wheel is in pressure contact with the cup-shaped wheel retainer 20. The pins 29 transmit the load and there is no necessity for relying upon excessive frictional pressure for driving power.

In accordance with the patent statutes I have described and illustrated the preferred embodiment of my invention, but it will be understood that various changes and modifications can be made therein without departing from the spirit of the invention as defined by the appended claims.

I claim:

1. In a grinding mechanism having grinding wheels, releasable mounting means for said grinding wheels, said mounting comprising a rotatably supported cup-shaped wheel retainer, a grinding wheel having an outside diameter adapted to enter said retainer, said grinding wheel having a hollow portion at the face opposite said retainer, said grinding wheel having keyways extending therethrough and being positioned diametrically thereof, said cup-shaped retainer having apertures in alinement with said keyways, a disk having a central aperture and pins integral therewith and positioned diametrically thereof, said pins being in alinement with said keyways and with said apertures in said retainer, and releasable means threaded into said retainer and passing through said central aperture in said disk for releasably securing said grinding wheel to said wheel retainer.

2. In a grinding mechanism having grinding wheels, releasable mounting means for said grinding wheels, said mounting comprising a rotatably supported cup-shaped wheel retainer, a grinding wheel having an outside diameter adapted to enter said retainer, said grinding wheel having a hollow portion at the face opposite said retainer, said grinding wheel having keyways extending therethrough and being positioned diametrically thereof, said cup-shaped retainer having apertures in alinement with said keyways, a disk having a central aperture and pins integral therewith and positioned diametrically thereof, said pins being in alinement with said keyways and with said apertures in said retainer, releasable means threaded into said retainer and passing through said central aperture in said disk for releasably securing said grinding wheel to said wheel retainer and resilient means having lateral waves and being positioned between the inner face of said wheel retainer and said grinding wheel for automatically compensating for shock to said grinding wheel.

NATHAN OBEDIN.
